REMOTE CONTROL SYSTEM

Daniel G. Taylor, Minneapolis, Minn., assignor to
 Minneapolis-Honeywell Regulator Company,
 Minneapolis, Minn., a corporation of Delaware

Application April 8, 1935, Serial No. 15,264

16 Claims. (Cl. 236—74)

The present invention relates to electrical systems of control by which a device or mechanism to be controlled may be "modulated" or "proportioned". In systems of this type, it is now common practice to provide one or more variable resistance controllers which control the respective energization of a pair of electrical oppositely acting devices that operate a switching mechanism which in turn, either directly or through the medium of a relay, control motor means that positions the device to be controlled or operated, this same switching mechanism also being controlled by the motor means either mechanically, or electrically by having the motor means control a further variable resistance that is associated with the oppositely acting devices so as to rebalance the energizations of the same when the device to be controlled or operated has been properly positioned.

In such arrangements, the switching mechanism that operates the motor means, either directly or indirectly, and the oppositely acting electrical means for controlling the same, are operated to various circuit controlling positions by reasons of relatively small changes in the associated controlling variable resistances and might be termed a "marginal" device or mechanism in that the switch arm of the switching mechanism is very gradually and slowly moved towards and away from the associated contact or contacts so that the contact pressure at the moment of the original engagement or disengagement of the switch arm and associated contact or contacts is very light, thereby making such switching mechanism extremely sensitive to vibrations and the like. In order to overcome this difficulty in commercial apparatus of this nature, it has been usual to provide some means for increasing the contact pressure between the switch arm of the switching mechanism and the associated contact or contacts whenever a circuit is completed therethrough.

In the past, one form of contact pressure increasing arrangement has included small auxiliary electrical devices which cooperate with the oppositely acting electrical devices and are energized upon engagement of the switch arm of the switching mechanism with its associated contact or contacts and are deenergized upon disengagement of such parts. Another form has taken the form of connections between such switching mechanism and a portion of the oppositely acting electrical devices whereby such portions are additionally energized upon engagement of the switch arm of the switching mechanism and its contact

or contacts. While these arrangements are entirely satisfactory from an operating standpoint, they are relatively expensive from a production standpoint. The present invention relates to an improved and simplified arrangement for obtaining increased contact pressure in arrangements of the type discussed above. 5

An object of the present invention, therefore, is the provision of a simplified and improved contact pressure increasing arrangement for use in electrical systems of the "proportioning" or "modulating" type, the new and improved arrangement being such as to readily adapt itself to high quantity production. 10

A further object of the invention is the provision of an electrical "proportioning" or "modulating" system employing a switching mechanism operated by normally balanced oppositely acting electrical devices in which resistance means are associated with the switching mechanism in such manner that engagement of the switch arm thereof with an associated contact as the result of unbalance of the normally balanced oppositely acting electrical means causes a further unbalance thereof in the same direction without the use of auxiliary electrical devices and without the necessity of connecting such resistance means intermediate the ends of the windings of the normally balanced oppositely acting electrical devices. 15 20 25

Further objects of the invention will be found in the drawing, the description and the accompanying claims. 30

For a more complete understanding of the invention, reference may be had to the following detailed description and the accompanying drawings in which: 35

Fig. 1 shows the invention applied to an electrical proportioning or modulating system of the electrically balanced type, and

Fig. 2 shows the invention applied to an electrical modulating or proportioning system of the mechanically balanced type. 40

The systems of the present invention have particular utility in the field of air conditioning for controlling dampers, valves and the like and such an application of the systems of the present invention has been shown in Fig. 1 of the drawing. Referring to Fig. 1, a device for controlling a condition has therein been shown in the form of a valve indicated at 10. The valve 10 may be utilized to control the flow of fuel to a burner, the flow of a heating or cooling medium to suitable heat transferring apparatus, or in any other desired manner. 45 50

The valve 10 is shown as provided with a suitable

ble valve stem 11 which is connected to a rack 12. Cooperating with the rack 12 of the valve 10 is a pinion 13 which is carried by and secured to a main operating shaft 14. The main operating shaft 14 is connected to a suitable reversible motor means through reduction gearing generally indicated at 15. In the apparatus of Fig. 1, the reversible motor means is shown as comprising a pair of oppositely acting induction motors having rotors 16 and 17, both of which are secured to a common rotor shaft 18. Field windings 19 and 20 cooperate with the respective rotors 16 and 17.

Energization of the field windings 19 and 20 is herein shown as controlled by a relay which is illustrated as being of the electromagnetic type although it will be readily understood that any other suitable type of relay could be utilized. This relay includes a pair of relay windings 22 and 23 which control a single plunger 24. The windings 22 and 23 may be entirely separate or may be obtained by providing a single winding with a center tap. The plunger 24 is connected to a relay switch arm 25 through a suitable connecting means 26. The switch arm 25 cooperates with a pair of spaced stationary contacts 27 and 28. Contact 27 is connected to one end of field winding 19 by means of a wire 29 and contact 28 is similarly connected to one end of field winding 20 by a wire 30. The other ends of the field windings 19 and 20 are both connected to a line wire 31 by means of a wire 32 and the switch arm 25 is connected to a line wire 33 by a wire 34. It will be readily apparent that upon engagement of switch arm 25 with contact 27, the field winding 19 is energized and that, upon engagement of switch arm 25 with contact 28, the field winding 20 is energized.

The relay windings 22 and 23 are controlled by a switching mechanism comprising a switch arm 35 that is pivoted at 36 and which cooperates with spaced contacts 37 and 38. The switch arm 35 is connected to a plunger 39 by suitable connecting means 40 and this plunger 39 is controlled by a pair of normally balanced oppositely acting electrical devices, herein shown in the form of a pair of electromagnetic windings 41 and 42. The windings 41 and 42, as in the case of windings 22 and 23, may be entirely separate or may take the form of a single winding that is provided with a center tap. It is to be understood that the switch arm 35 could be controlled by oppositely acting electrical devices other than of the electromagnetic types.

The energizations of the windings 41 and 42 are controlled, in part, by a variable resistance type of controller herein shown as a potentiometer thermostat. This potentiometer thermostat includes an actuating element 45, herein shown as comprised of bimetal and having one of its ends secured as at 46. The other end of bimetallic element 45 operates a control contact arm 47 which, upon temperature changes, sweeps back and forth across a control resistance 48. In the electrically balanced type of system shown in Fig. 1, the energization of windings 41 and 42 are also controlled, in part, by a variable balancing resistance means, herein shown as comprising a potentiometer which includes a balancing resistance 49 that is adapted to be traversed by a balancing contact arm 50 which is secured to the main operating shaft 14.

The line wires 31 and 33 supply power to a step-down transformer 52, having a high voltage primary 53 and a low voltage secondary 54. The

windings 41 and 42, in series, are connected across the secondary 54 of transformer 52 by means of wires 55, 56, 57 and 58. Similarly, the relay windings 22 and 23, in series, are connected across the secondary of transformer 52 by wires 55, 59, 60, 61, 62 and 58. The control resistance 48 and the balancing resistance 49, in parallel, are connected in parallel with the series connected windings 41 and 42 through protective resistances, 63 and 64 by means of wires 65, 66, 67, 68, 69 and 70. The control and balancing contact arms 47 and 50 are connected to the junction of windings 41 and 42 by means of wires 71, 72, 73 and 74. The junction of relay windings 22 and 23 is connected to the switch arm 35 through a protective resistance 75 and the switch arm 35 is connected to the junction of wires 71 and 72 through a resistance means 76 by means of wires 77 and 78. The contact 37 is connected to the junction of wires 61 and 62 by a wire 79 and the junction of wires 59 and 60 is similarly connected to contact 38 by a wire 80.

Operation of the system of Fig. 1

The bimetallic element 45 of the potentiometer thermostat may respond to any desired temperature condition, such, for instance, as the temperature of a space to be controlled and, with the parts in position shown, this temperature is intermediate the permissible or desired high and low limits. As a result, control contact arm 47 is 30 engaging the central portion of control resistance 48. Similarly, the balancing contact finger 50 is engaging the central portion of balancing resistance 49. The two windings 41 and 42 are therefore equally energized and the plunger 39 35 is in a central position so that switch arm 35 is intermediate contacts 37 and 38 and is not engaging either one of them. As a result, relay windings 22 and 23 are equally energized and the plunger 24 is in a central position whereby switch 40 arm 25 is intermediate contacts 27 and 28. Field windings 19 and 20 are therefore both deenergized and the main operating shaft 14 is stationary. With the parts in this position, the valve 10 is open to a predetermined extent, for instance, half open, so as to permit a predetermined heating or cooling of the space to be controlled.

Now if the temperature to which bimetallic element 45 responds should fall, control contact arm 51 56 will move along control resistance 48 towards the right hand end thereof. Such movement of control contact arm 47 rearranges the resistance connected in circuit with the windings 41 and 42 in such manner that the winding 41 becomes 56 more highly energized than winding 42. Plunger 39 therefore moves to the left and when this unbalance in the energizations of windings 41 and 42 has become sufficient, switch arm 35 will lightly engage contact 38. When this occurs, relay 60 winding 22 is substantially short-circuited, complete short-circuiting being prevented by the protective resistance 75. By proper design of the relay windings 22 and 23, this protective resistance 75 could be omitted but it has been found 65 more commercially practicable to make the relay windings 22 and 23 of relatively low impedance so that the use of a protective resistance is desirable. It will be noted that current can now flow from the secondary 54 of transformer 52 70 by way of wires 58, 62, and 61 through relay winding 23 at which point the circuit branches and a part thereof goes by way of relay winding 22, wire 60, wire 59, wire 55 to the other side of secondary 54 whereas the other part goes through 75

protective resistance 75, switch arm 35, contact 38, wire 80, wire 59 and wire 55 to the same side of secondary 54. Relay coil 23 is therefore more highly energized than relay coil 22, whereupon plunger 24 is forcibly moved in a right hand direction sufficiently far to bring switch arm 25 into solid and firm engagement with contact 28. Field winding 20 is thereupon energized by the following circuit: line wire 33, wire 34, relay switch arm 25, contact 28, wire 30, field winding 20 and wire 32 to line wire 31.

It will be noted that engagement of switch arm 35 with contact 38 also caused resistance 76 to be connected in parallel with the winding 42. The left hand end of winding 42 and the upper end of resistance 76 are permanently interconnected by wires 74 and 72 and 78, whereas the right hand end of winding 42 and the lower end of resistance 76 are now interconnected by wires 56, 59 and 80, contact 38, switch arm 35 and wire 77. This placing of resistance 76 in parallel with the winding 42 causes a further reduction in the current flowing therethrough, whereupon plunger 39 pulls switch arm 35 firmly into engagement with contact 38. In this manner, the contact pressure between switch arm 35 and the contact 38 is increased so that a good firm contact is made and all possibility of chatter is eliminated.

Energization of the field winding 20 causes rotation of motor rotor 17 in such a direction as to rotate main operating shaft 14 in a clock-wise direction when viewed from the left. Balancing contact arm 50 therefore moves upwardly along balancing resistance 49 and gradually rebalances the energization of windings 41 and 42. When the energizations of windings 41 and 42 have been sufficiently rebalanced, plunger 39 will have moved to the right sufficiently to separate switch arm 35 from contact 38. When this occurs, relay windings 22 and 23 are again connected across the secondary 54 of transformer 52 in series so that they are equally energized. Plunger 24 then returns to the position shown whereupon field winding 20 is deenergized. Separation of switch arm 35 from contact 38 also disconnects the right hand end of winding 42 from the lower end of resistance 76 whereby the current flow through winding 42 is increased so that the plunger 39 moves further towards the right and increases the space between switch arm 35 and contact 38.

This clockwise movement of main operating shaft 14 caused an upward movement of rack 12 whereupon valve 10 was opened more widely. Valve 10 is now in a more widely open position so that more heat is supplied to the space to be controlled whereby to counter-act the fall in temperature which caused control contact arm 47 to move along control resistance 48 towards the right hand end thereof.

If the temperature of the space being controlled should fall to the permissible minimum, control contact arm 47 will move to the extreme right hand end of control resistance 48 whereupon winding 42 will be substantially completely short-circuited, complete short-circuiting being prevented by reason of the protective resistance 64. Under these conditions, it will be noted that the protective resistance 64 and the winding 42 are connected directly in parallel, the junction of winding 41 and 42 being connected to the upper end of protective resistance 64 by means of wire 74, wire 73, bimetallic element 45, control contact arm 47 and wire 68, whereas the right hand end of winding 42 is connected to the lower end of protective resistance 64 by wire 70. Plunger 39

will again move to the left so as to bring switch arm 35 into engagement with contact 38 whereupon field winding 20 will be energized again. Resistance 76 will again be placed in parallel with winding 42 whereupon the current flow therethrough is further reduced so that the contact pressure between switch arm 35 and contact 38 is again increased as explained above. The main operating shaft 14 will now be rotated in a clockwise direction until balancing contact finger 50 engages the extreme upper end of balancing resistance 49 whereupon winding 41 will be substantially short-circuited, complete short circuiting being prevented by protective resistance 63 which is placed in parallel therewith as will be evident upon an inspection of the wiring diagram. The system will then again be rebalanced and the field winding 20 will be de-energized. At this time, the valve 10 has been moved to full open position. It will be readily apparent, that a suitable limit switch may be utilized if desired to limit the extreme movement of main operating shaft 14 in clockwise direction and that a similar limit switch may be utilized to limit the extreme counter-clockwise movement of main operating shaft 14 in the opposite direction.

Whenever the temperature to which bimetallic element 45 responds rises, control contact arm 47 will move along control resistance 48 towards the left hand end thereof whereupon winding 42 will become more highly energized than winding 41. Plunger 39 thereupon will move toward the right and switch arm 35 is slowly and gradually moved toward contact 37 until the two engage. When this occurs, protective resistance 75 will be placed in parallel with relay winding 23 so that relay 22 becomes more highly energized and plunger 24 moves quickly to the left thereby bringing relay switch arm 25 into firm engagement with contact 27. Field winding 19 is thereupon energized by a circuit as follows: line wire 33, wire 34, relay switch arm 25, contact 27, wire 29, field winding 19 and wire 32 to line wire 31. Rotor 16 therefore rotates in a direction such as to cause rotation of main operating shaft 14 in a counter-clockwise direction as viewed from the left.

Engagement of switch arm 35 with contact 37 also places resistance 76 in parallel with winding 41. The right hand end of winding 41 or the junction of windings 41 and 42 is connected to the upper end of resistance 76 by wire 74, wire 72 and wire 78 as before explained. The left hand end of winding 41 is now connected to the lower end of resistance 76 by wire 57, wire 62, wire 79, contact 37, switch arm 35 and wire 77. The flow of current through winding 41 is thereby further reduced so that plunger 39 forces switch arm 35 into firm contact with contact 37.

This counter-clockwise movement of main operating shaft 14 will continue until balancing contact arm 50 has been moved downwardly along balancing resistance 49 sufficiently to substantially rebalance the energizations of windings 41 and 42 so that plunger 39 moves towards the left far enough to just separate switch arm 35 from contact 37. When this occurs, the energizations of relay windings 22 and 23 will again be rebalanced so that relay switch arm 25 disengages contact 27 and field winding 19 is de-energized. Separation of switch arm 35 from contact 37 also disconnects the lower end of resistance 76 from the left hand end of winding 41 so that the resistance 76 and winding 41 are no 75

longer connected in parallel whereupon the energization of winding 41 will increase somewhat. As a result, switch arm 35 moves further away from contact 37 so that the same are sufficiently 5 widely spaced apart to prevent an immediate reengagement without any further temperature change. This counter-clockwise change movement of main operating shaft 14 caused a downward movement of rack 12 so that valve 10 was 10 partially closed.

In this manner, by the simple inclusion of a single resistance 76 through novel and extremely simple circuit connections, an increased contact pressure is provided between switch arm 35 and its cooperating contacts 37 and 38 without resorting to the use of auxiliary winding and without running connections intermediate the ends of windings 41 and 42. The apparatus can therefore be built more readily and with a smaller expenditure of time and therefore at a lesser 20 cost.

Turning now to Fig. 2 of the drawing, a modified arrangement is disclosed wherein the invention is applied to an electrical proportionating or modulating system of the mechanical follow-up type, the intermediate relay also being omitted. In this modification, there is a main operating shaft 85 which may be utilized to drive any suitable device such as the valve 10 of Fig. 1. This 25 main operating shaft 85 is connected to a rotor shaft 86 through suitable reduction gearing generally indicated at 87. Two rotors 88 and 89 are carried by and secured to rotor shaft 86 and are respectively provided with cooperating field 30 windings 90 and 91. These motors, comprised by the rotors 88 and 89 and the associated field windings 90 and 91, are of equal power and are arranged to rotate in opposite directions upon energization. The field windings 90 and 91 are 35 normally constantly energized by being connected in series across the secondary 92 of a step-down transformer 93 having a high voltage primary 94 that is connected to suitable line wires 95 and 96. The series circuit by which the field windings 90 and 91 are normally connected in series across 40 the secondary 92 is as follows: secondary 92, wire 97, wire 98, wire 99, field winding 90, field winding 91, wire 100, wire 101 and wire 102 to the other side of secondary 92.

The field windings 90 and 91 normally both 45 being energized to the same extent, their associated rotors 88 and 89 exert equal and oppositely acting torques upon the rotor shaft 86 whereby the main operating shaft 85 normally remains stationary. These field windings 90 and 91 are 50 adapted to be selectively short-circuited whereby one or the other of them is operatively deenergized so that the other is rendered capable of rotating the main operating shaft 85. This selective short-circuiting is accomplished by suitable switching mechanism that includes a suitable segmental plate 105 which is pivoted at 106 and is provided with suitable teeth 107 which cooperate with a worm 108 that is mounted upon 55 and secured to the main operating shaft 85. Mounted upon plate 105 at a point indicated at 109 is a flexible switch arm 110 which is adapted to cooperate with a pair of spaced contacts 111 and 112 that are carried by the plate 105.

The switch arm 110 is controlled by a pair of 60 oppositely acting electrical devices herein shown as comprising a pair of windings 113 and 114 which may either take the form of separate windings or may be obtained by providing a single winding with center tap. These two windings

113 and 114 control the position of a single plunger 115 which is connected to the switch arm 110 through suitable connecting means indicated at 116. These windings 113 and 114 are connected across the secondary 92 of transformer 93, in 5 series, by wire 97, wire 117, wire 118 and wire 102.

The respective energization of windings 113 and 114 may be controlled by any suitable controlling device which is herein shown in the form of a potentiometer thermostat. This potentiometer thermostat includes a temperature responsive element 119 shown in the form of a curved bimetallic strip which has one of its ends secured as indicated at 120. The other end of bimetallic strip 119 carries a controlling contact arm 121 which is adapted to sweep back and forth across an associated control resistance 122 upon changes in temperature. The control resistance 122 is connected in parallel with the series connected windings 113 and 114, and preferably through 20 protective resistances 123 and 124, by means of wires 125, 126, 127 and 128. The bimetallic strip 119, and therefore the control contact arm 121, is connected to the junction of windings of 113 and 114 by means of wires 129 and 130. 25

Switch arm 110 is connected to the junction of field windings 90 and 91 by means of wires 131 and 132. The other end of field winding 90 is connected to contact 111 by means of wires 99 and 133 whereas the other end of field winding 91 is connected to contact 112 by means of wires 100 and 134.

In order to provide for increased contact pressure between switch arm 110 and its associated contacts 111 and 112, in a manner that will hereinafter be set out in detail, a resistance 135 is connected to the junction of wires 131 and 132 by means of a wire 136 and is connected to the junction of windings 113 and 114 by being connected to the junction of wires 129 and 130 by 40 means of a wire 137.

Operation of the system of Fig. 2

With the parts in the position shown, the temperature to which bimetallic strip 119 responds is 45 intermediate or normal so that the controlling contact finger 121 engages the center of control resistance 122. Windings 113 and 114 are therefore equally energized and the switch arm 110 is in a vertical position. The plate 105 is in such 50 position that contacts 111 and 112 are both out of engagement with the switch arm 110. As a result, field windings 90 and 91 are connected in series across the secondary 92 of transformer 93 whereby they are equally energized and the main 55 operating shaft 85 is stationary. With the parts in this position, assuming that the main operating shaft 85 controls the valve 10 of Fig. 1, the valve would be in half open position. If the temperature to which bimetallic element 119 responds should now rise, control contact finger 121 will 60 move along control resistance 122 towards the right hand end thereof. As a result, less resistance will be placed in parallel with the winding 113 whereby a smaller amount of current will 65 flow through the winding 113, and similarly a greater amount of resistance will be placed in parallel with the winding 114 whereby a greater amount of current will flow through this winding. The plunger 115 therefore moves towards the left 70 and in so doing flexes switch arm 110 to the left of its vertical position and towards the contact 112. When the temperature to which bimetallic element 119 has lowered sufficiently, the plunger 115 will have moved to the left far enough to

bring switch arm 110 into engagement with contact 112. When this occurs, field winding 91 is short circuited by the following circuit: from the right hand end of field winding 91, wire 110, wire 134, contact 112, switch arm 110, wire 131, and wire 132 to the left hand end of field winding 91. The field winding 90 is therefore effective to rotate its associated rotor 88 in such a direction as to cause counter-clockwise rotation of the main operating shaft 85 when viewed from the left. Such rotation of main operating shaft 85 moves the valve being controlled to a more nearly closed position and at the same time causes counter-clockwise rotation of plate 105 about its pivot 106, whereby contact 112 is moved in a direction to separate from the switch arm 110.

Engagement of switch arm 110 with contact 112 also operated to place the resistance 135 in parallel with the winding 113. It will be noted that the left hand end of winding 113 or the junction between windings 113 and 114 is continuously connected to the left hand end of resistance 135 by wires 130 and 137. With the switch arm 110 engaging contact 112, the right hand end of winding 113 is connected to the right hand end of resistance 135 by wires 118, 101, wire 134, contact 112, switch arm 110, wire 131 and wire 136. Connecting of resistance 135 in parallel with winding 113 further reduces the current flow therethrough whereupon plunger 115 tends to move further towards the left whereby switch arm 110 was brought firmly into engagement with contact 112. In this manner, immediately upon engagement of switch arm 110 with contact 112, the contact pressure therebetween was increased. As a result, the main operating shaft 85 must move to such position that contact 112 separates from switch arm 110 when switch arm 110 reaches the position it is caused to assume under the action of its further movement of plunger 115 towards the left by reason of replacing of resistance 135 in parallel with the winding 113. When this occurs, contact 112 will separate from switch arm 110 whereupon the short-circuit from field winding 91 is interrupted. Field windings 90 and 91 are therefore again equally energized and further rotation of the main operating shaft ceases. Separation of contact 112 with switch arm 110 likewise results in breaking the connection that places resistance 135 in parallel with winding 113. The current flow through winding 113 is therefore increased whereupon plunger 115 moves a small amount towards the right, thereby separating switch arm 110 more widely from contacts 112.

It will be evident, as the temperature continues to rise, the main operating shaft 85 will be moved further and further in counter-clockwise direction as viewed from the left whereby the associated valve or other device being controlled will be correspondingly positioned. Upon a fall in the temperature to which bimetallic element 119 responds, the control contact arm 121 will move along control resistance 122 towards the left hand end thereof whereupon the flow of current through winding 114 will be decreased and the flow of current through winding 113 will be increased in the manner which will now be apparent. As a result, plunger 115 will move towards the right thereby moving switch arm 110 towards contact 111. When this fall in temperature has been sufficiently great, the switch arm 110 will engage contact 111 whereupon the field winding 90 will be short-circuited. It will be seen that the left hand end of field winding 90 is

now connected to the right hand end thereof by means of wires 99 and 133, contact 111, switch arm 110, wire 131 and wire 132. The field winding 91 therefore is rendered operative to rotate rotor 89 in such a direction that main operating shaft 85 rotates in a clockwise direction as viewed from the left. This motion is transmitted to the device being controlled and if the valve 10 of Fig. 1 is being controlled by the main operating shaft 85, this valve thereupon opens more widely. Such rotation of main operating shaft 85 rotates plate 105 about its pivot 106 in a clockwise direction.

Engagement of contact 111 by switch arm 110 also connected resistance 135 in parallel with the winding 114. The right hand end of winding 114 is connected to the left hand end of resistance 135 at all times by wires 130 and 137, and the left hand end of winding 114 is now connected to the right hand end of resistance 135 by means of wire 117, wire 98, wire 133, contact 111, switch arm 110, wire 131, and wire 136. Placing of resistance 135 in parallel with winding 114 further reduces the current flow through winding 114 whereupon plunger 115 tends to move further towards the right whereby switch arm 110 is brought into firm solid engagement with contact 111. The main operating shaft 85 must therefore continue with clockwise rotation until contact 111 moves away from switch arm 110 when switch arm 110 is in the new position demanded by the relative energizations of windings 113 and 114.

When main operating shaft 85 has been moved this far in clockwise direction, so that contact 111 is moved from engagement from switch arm 110, the short-circuit for field winding 90 is interrupted whereupon field windings 90 and 91 are again equally energized by being connected in series across the secondary 92 so that further rotation of main operating shaft 85 ceases. This separation of contact 111 and switch arm 110 also disconnected the left hand end of winding 114 from the right hand end of resistance 135 whereby the resistance 135 is no longer connected and parallel with the winding 114. As a result, the current flow through winding 114 increases and the plunger 115 moves towards the left a small amount thereby widely separating switch arm 110 from contact 111.

It will be evident that as the controlling temperature continues to fall, the main operating shaft will be given further movements in a clockwise direction. Suitable limit switches may be provided, if desired, to limit the extreme movements of the main operating shaft 85 in a manner well known in the art. It will be noted that no protective resistance has been utilized in the shunt circuits by which the field windings 90 and 91 are operatively deenergized. This is because the motor field windings are of sufficiently high impedance to permit their being connected singly across the secondary of transformer of 92. The protective resistances 123 and 124 which are connected between the windings 113 and 114 and the controlling resistance 122 prevents the complete short-circuiting of either of these windings 113 and 114 since these coils are designed so as to be of a desired special size and impedance and they should not be connected directly across the secondary of transformer 92 singly.

From the foregoing, it will be apparent that by this invention I provide a very simple arrangement which adapts itself to high production by which the contact pressure between a switch

arm and an associated contact is increased upon engagement of such switch arm and contact and by which the space between such switch arm and contact is instantly widened upon separation thereof. The use of this simplified arrangement eliminates the necessity of providing auxiliary electrical devices or electro-magnetic coils and also eliminates the necessity of tapping into a portion of the opposed electrical devices or electro-magnetic coils in the case auxiliary coils are not utilized.

It will be appreciated that the present invention is applicable to any arrangement in which a pair of contacts are slowly brought into engagement as a result of a gradual variation in the electrical current flowing to a device which controls one or more of these contacts. The two modifications herein shown therefore are to be taken as merely illustrative of two forms which the invention may take and I am to be limited only by the scope of the appended claims.

I claim:

1. In an air conditioning system, an element in control of the condition of a space to be controlled, electrical means in control of said element, a switch in control of said electrical means, a variably energizable electrical device in control of said switch, a condition responsive means in control of the energization of said device for varying the current flow thereto, and resistance means associated with said device and controlled by said switch, arranged to vary the current flow through said device, upon closure of said switch, in such manner as to increase the contact pressure of said switch.

2. In an air conditioning system, an element in control of the condition of a space to be controlled, electrical means in control of said element, a switch in control of said electrical means, a variably energizable electrical device in control of said switch, a condition responsive means in control of the energization of said device for varying the current flow thereto, resistance means associated with said device and controlled by said switch, arranged to vary the current flow through said device, upon closure of said switch, in such manner as to increase the contact pressure of said switch, and means operated by said electrical means to cause opening of said switch.

3. In an air conditioning system, an element in control of the condition of a space to be controlled, electrical means in control of said element, a switch in control of said electrical means, a variably energizable electrical device in control of said switch, a condition responsive means in control of the energization of said device for varying the current flow thereto, resistance means associated with said device and controlled by said switch, arranged to vary the current flow through said device, upon closure of said switch, in such manner as to increase the contact pressure of said switch, and means controlled by said electrical means to vary the current flow through said device in a manner to cause opening of said switch.

4. In an air conditioning system, an element in control of the condition of a space to be controlled, electrical means in control of said element, a switch in control of said electrical means, a variably energizable electrical device in control of said switch, a condition responsive means in control of the energization of said device for varying the current flow thereto, resistance means associated with said device and controlled by said switch, arranged to vary the cur-

rent flow through said device, upon closure of said switch, in such manner as to increase the contact pressure of said switch, and mechanical connections between said electrical means and switch to cause opening of said switch.

5. In combination, reversible motor means, double circuit switching means in control thereof, a pair of oppositely acting electrical devices in control of said switching means, a controller electrically associated with said devices and arranged to vary the respective energizations thereof whereby to cause movement of said switching means to closed circuit positions, resistance means associated with said devices controlled by said switching means and operated to further vary the respective energizations of said devices in a direction to increase the contact pressure in said switching means upon closure of either of its circuits, an element to be controlled, electrical means associated with said devices to balance the energizations thereof and mechanical connections between said reversible motor means, said element to be controlled and said last-named electrical means.

6. In combination, reversible motor means, double circuit switching means in control thereof, a pair of oppositely acting electrical devices in control of said switching means, a controller electrically associated with said devices and arranged to vary the respective energizations thereof whereby to cause movement of said switching means to closed circuit positions, resistance means associated with said devices controlled by said switching means and operated to further vary the respective energizations of said devices in a direction to increase the contact pressure in said switching means upon closure of either of its circuits, an element to be controlled, and mechanical connections between said element to be controlled and said switching means operative simultaneously to position said element and operate said switching means to open circuit position.

7. In combination, a pair of oppositely acting electrical devices, double-circuit switching means controlled thereby and arranged to be in open circuit position when said devices are substantially equally energized and to selectively close first and second circuits when a first of said devices is energized sufficiently more highly than a second of said devices and vice versa, a variable electrical controller associated with said devices and operable to vary the relative energizations of the same, resistance means associated with said devices rendered operable upon closure of either circuit by said switching means to further vary the energizations of said devices in a manner to increase the contact pressure in said switching means, reversely acting electrical means controlled by said switching means, an element to be positioned, variable electrical balancing means associated with said devices for balancing the energizations of the same, and operative connections between said reversely acting electrical means, element to be positioned and variable electrical balancing means.

8. In combination, a pair of oppositely acting electrical devices, double-circuit switching means controlled thereby, a variable electrical controller associated with said devices and operable to vary the relative energizations of the same, resistance means associated with said devices rendered operable upon closure of either circuit by said switching means to further vary the energizations of said devices in a manner to increase

the contact pressure in said switching means, reversely acting electrical means controlled by said switching means, an element to be positioned, and connections between said reversely acting electrical means, element to be positioned, and switching means.

9. In combination, a pair of oppositely acting electrical devices, a variable resistance controller electrically connected thereto and operable to vary the respective energizations thereof, a switch controlled by the cooperative action of said devices, resistance means connected to said devices and switch in a manner to increase the contact pressure of said switch by further varying the energizations of said devices upon closure of the switch, electrical means also controlled by said switch, an element to be positioned, means to cause opening of said switch, and connections between said electrical means, element to be positioned, and switch opening means.

10. In combination, a pair of oppositely acting electrical devices connected in series across a source of power, a control potentiometer including a control resistance and a control contact movable in respect to each other, connections connecting said control resistance in parallel with the series connected electrical devices and connecting the control contact to the junction of said electrical devices, double circuit switching means controlled by the conjoint action of said electrical devices, a single resistance having one end thereof connected to the junction of said electrical devices and its other end connected to the common connection of said double circuit switching means, two-coil electrical means controlled by said double circuit switching means, connections by which said switching means respectively operatively energizes one or the other of said coils of the two-coil electrical means and places said resistance in parallel with one or the other of said electrical devices, an element to be controlled, means to open said switching means, and connections between said two-coil electrical means, element, and switch opening means.

11. In combination, a pair of oppositely acting electrical devices connected in series across a source of power, a control potentiometer including a control resistance and a control contact movable in respect to each other, connections connecting said control resistance in parallel with the series connected electrical devices and connecting the control contact to the junction of said electrical devices, double circuit switching means controlled by the conjoint action of said electrical devices, a single resistance having one end thereof connected to the junction of said electrical devices and its other end connected to the common connection of said double circuit switching means, two-coil electrical means controlled by said double circuit switching means, connections by which said switching means respectively operatively energizes one or the other of said coils of the two-coil electrical means and places said resistance in parallel with one or the other of said electrical devices, an element to be controlled, variable resistance means associated with said electrical devices and operable to vary the respective current flows thereto, and connections between said two-coil electrical means, element to be positioned and said variable resistance means.

12. In combination, a pair of oppositely acting electrical devices connected in series across a source of power, a control potentiometer including a control resistance and a control contact

movable in respect to each other, connections connecting said control resistance in parallel with the series connected electrical devices and connecting the control contact to the junction of said electrical devices, double circuit switching means controlled by the conjoint action of said electrical devices, a single resistance having one end thereof connected to the junction of said electrical devices and its other end connected to the common connection of said double circuit switching means, two-coil electrical means controlled by said double circuit switching means, connections by which said switching means respectively operatively energizes one or the other of the coils of said two-coil electrical means and places said resistance in parallel with one or the other of said electrical devices, an element to be controlled, a balancing potentiometer including a balancing resistance and a balancing contact movable in respect to one another, connections between said balancing potentiometer and electrical devices by which the respective energizations of said devices may be varied by the balancing potentiometer, and connections between said two-coil electrical means, said element to be positioned and the balancing potentiometer.

13. In combination, a pair of oppositely acting electrical devices connected in series across a source of power, a control potentiometer including a control resistance and a control contact movable in respect to each other, connections connecting said control resistance in parallel with the series connected electrical devices and connecting the control contact to the junction of said electrical devices, double circuit switching means controlled by the conjoint action of said electrical devices, a single resistance having one end thereof connected to the junction of said electrical devices and its other end connected to the common connection of said double circuit switching means, two-coil electrical means controlled by said double circuit switching means, connections by which said switching means respectively energizes one or the other of said coils of the two-coil electrical means and places said resistance in parallel with one or the other of said electrical devices, an element to be controlled, means to open said switching means, and connections between said two-coil electrical means, element, and switch opening means.

14. In combination, a first pair of oppositely acting electrical devices connected in series across a source of power, a controlling potentiometer including a control resistance and an associated contact, connections connecting the control resistance in parallel with the series connected electrical devices and the associated contact to the junction of said electrical devices, a first double circuit switching mechanism controlled by said electrical devices, a second pair of oppositely acting electrical devices also connected in series across said source of power, a single resistance connected to the junction of said first electrical devices and to the common terminal of said first double circuit switching mechanism, circuit connections respectively connecting the other two terminals of said double circuit switching mechanism with the second pair of electrical devices, a second double circuit switching mechanism controlled by said second pair of electrical devices, reversible motor means controlled by said second double circuit switching mechanism, means associated with said first double circuit switching

mechanism controlled by said reversible motor means and operative to cause movement of said first double circuit switching mechanism to open circuit position, and an element to be positioned also controlled by said reversible motor means.

5 15. In combination, a first pair of oppositely acting electrical devices connected in series across a source of power, a controlling potentiometer including a control resistance and an associated contact, connections connecting the control resistance in parallel with the series connected electrical devices and the associated contact to the junction of said electrical devices, a first double circuit switching mechanism controlled by said electrical devices, a second pair of oppositely acting electrical devices also connected in series across said source of power, a single resistance connected to the junction of said first electrical devices and to the common terminal of said first double circuit switching mechanism, circuit connections respectively connecting the other two terminals of said double circuit switching mechanism with the second pair of electrical devices, a second double circuit switching mechanism controlled by said second pair of electrical devices, reversible motor means controlled by said second

double circuit switching mechanism, a balancing potentiometer including a balancing resistance and an associated contact, connections connecting said balancing resistance in parallel with the first series connected electrical devices and the associated contact with the junction thereof, an element to be positioned, and mechanical connections between said reversible motor means and said balancing potentiometer and the element to be positioned.

10 15. In combination, a pair of oppositely acting electrical devices, a switch controlled thereby, control means associated with said devices to vary the respective energizations thereof in a manner to cause closure of said switch, an electrical mechanism, connections by which said mechanism is placed in circuit with the whole of one of said devices upon closure of said switch and in a manner to further vary the respective energizations of said devices in switch closing direction 20 whereby closure of said switch results in an increase in the pressure between the contacts thereof, electrical means controlled by said switch, and an element to be positioned controlled by said electrical means.

DANIEL G. TAYLOR. 25
